UNITED STATES PATENT OFFICE

119,785

DESIGN FOR A PHOTOGRAPHIC TANK

Clarence Karstadt, Glen Ellyn, Ill., assignor to
Sears, Roebuck and Co., Chicago, Ill., a corpora-
tion of New York

Application August 2, 1939, Serial No. 86,427

Term of patent 3½ years

To all whom it may concern:

Be it known that I, Clarence Karstadt, a citizen of the United States, residing at Glen Ellyn, in the county of Du Page and State of Illinois, have invented a new, original, and ornamental Design for a Photographic Tank, of which the following is a specification, reference being had to the accompanying drawing, forming a part thereof,

Fig. 1 is a plan view of a photographic tank embodying my new design.

Fig. 2 is an elevation of the same.

Fig. 3 is a fragmentary sectional view taken as indicated by the line 3—3 in Fig. 1.

I claim:

The ornamental design for a photographic tank, substantially as shown.

CLARENCE KARSTADT.
